5 Claims. (Cl. 230—141)

The present invention relates to a rotary piston compressor with rotary pistons eccentrically arranged one within the other and meshing with each other. More specifically, the present invention concerns a specific embodiment of the inlet and outlet openings of rotary piston compressors of the above mentioned type while the inner wall surface of the outer rotary piston has the contour of a trochoid, whereas the wall surface of the inner rotary piston has the contour of enveloping curves.

Rotary piston compressors of the above mentioned type with inlet and outlet openings in the centers of the enveloping curves are known, which are evenly spaced from the adjacent tooth tips.

It is an object of the present invention to provide a rotary piston compressor of the above mentioned type, which will have an increased delivery.

It is another object of this invention to provide a rotary piston compressor which will be characterized by a greatly increased degree of efficiency.

These and other objects and advantages of the invention will appear more clearly from the following specification in connection with the accompanying drawing, in which:

FIG. 1 diagrammatically illustrates a cross section through a rotary piston compressor according to the present invention while said compressor occupies a position in which the piston is ahead of its dead center position by an angle of 30°.

FIG. 2 is a section similar to that of FIG. 1 showing the piston in its dead center position.

FIGS. 3 to 5 illustrate cross sections through a similar compressor which, however, in conformity with the present invention, is equipped with asymmetrically arranged openings. More specifically, FIG. 3 shows the piston 60° ahead of the dead center position; FIG. 4 shows the piston 30° ahead of the dead center position; FIG. 5 shows the piston in its dead center position.

FIGURE 6 illustrates a longitudinal section through a rotary piston compressor according to the present invention.

For purposes of increasing the delivery and the degree of efficiency of the compressor, it is suggested in conformity with the present invention to arrange the inlet and outlet openings asymmetrically between the tips of the inner rotary piston. More specifically, the said openings are so arranged that they are located in that portion of the enveloping curve which runs ahead. At the same time, that control edge which governs the discharge end has been displaced in the insert member in the direction of rotation of the rotary piston compressor.

According to a further development of the invention, each opening of the inner rotary piston starts approximately in the center of the enveloping curve and extends over approximately a quarter of the enveloping curve.

Furthermore, in conformity with the present invention, that opening edge which runs ahead or forms the front edge when looking in the direction of rotation of piston 2 is greatly rounded toward the enveloping curve of the inner rotary piston, and the opening edge which runs behind or forms the rear edge when looking in the

2

direction of rotation of piston 2 is provided with a sharp edge and a sharp angle with regard to the enveloping curve.

Referring now more specifically to the drawing, in all figures it is assumed that the outer rotary piston 1 rotates clockwise, and that the inner rotary pistons 2 and 3 are moved by the outer rotary piston 1 through the intervention of coupling gears at a transmission ratio of 2:3. The inner rotary piston 2 of FIGS. 1 and 2 comprises symmetrically arranged openings 4, whereas the openings 5 in the inner rotary piston 3 of FIGS. 3 to 5 are asymmetrically arranged in the running ahead portion of the enveloping curve 6. The tips of the inner rotary piston which are usually equipped with seals 7 subdivide the cylinder chamber into three working chambers 8, 9 and 10 in which in equal sequence there is effected the intake, the compression and the exhaust as well as the return expansion.

Within the inner rotary piston 2 there is provided an insert member 11, 12 which is fixedly connected to the housing lid and which comprises the inlet passage 13, 14 and the outlet passage 15, 16. The control edges of the passages 14 and 16 in the insert member 12 are in the same direction as the opening 5 displaced relative to the heretofore known arrangement as illustrated in FIGS. 1 and 2. The definition of the openings 4 according to FIGS. 1 and 2 is effected by the sharp edge or the somewhat rounded control edges 4a and 4b, whereas with the opening 5 according to FIG. 3 the running ahead control edge 5a merges with the enveloping curve 6 over a considerably rounded portion, while the lagging control edge 5b merges with the enveloping curve 6 along a sharp edge and a sharp angle. In view of these features, advantages are obtained during the intake over the entire intake stroke and also during the discharge of the working medium, especially near the dead center position. These advantages will presently appear.

During the intake stroke, the working medium enters through openings 4, 5 and passes into the suction chamber 8. The magnitude and the direction of the inlet velocity depend on the velocity of the working medium itself and on the superimposed rotary speed of the inner rotary pistons 2, 3 (see also FIGS. 2 and 5). According to FIG. 5, the working medium flows to an increased extent counter to the running ahead portion of the inner wall of the outer rotary piston 1 which defines the working chamber 8 (see FIG. 2). The flow pressure aids the rotary movement, and the flow conditions thus approach those of pure flow machines. The favorable effect of the present invention is further aided by the considerably rounded running ahead opening edge 5a and the sharp edged and sharp angled lagging edge 5b. The highly rounded running ahead edge 5a brings about a favorable radiation spread in the direction of rotation, whereas the sharp edged and sharp angled lagging edge 5b impedes the inflow of the taken-in working medium in the subsequent portion 8b of the working chamber 8. In this way, in this portion a lower pressure is formed than in the preceding portion 8a. This pressure drop aids in the rotary movement and in particular acts upon the inner rotary piston, while to a smaller extent it also acts upon the outer rotary piston. These conditions have been illustrated for the outer rotary piston by the higher pressure p_a' over the lower pressure p_a'' .

In conclusion it may be stated that the sharp edge 5b which impedes the flow will not cause any reduced filling of the intake chamber 8. Toward the end of the intake stroke, i.e. ahead and after the dead center position, the change in the working chamber is so small that a pressure increase including a post-charge in the entire suction chamber 8 can occur without difficulties.

The discharge operation is effected as follows. The

compressed working medium leaves the pressure chamber 10 through openings 4, 5 and passes into the pressure passage 15, 16. The working medium has to pass the running ahead control edge 4a, 5a and at the end of the discharge operation also has to pass the control edge 15a, 16a (see FIGS. 1 and 4). The cross sections which have to be passed through by the flow and which are defined by these control edges and the inner wall of the outer rotary piston and which are indicated by a dotted line 18, 19 are, according to FIG. 4, considerably greater than those of FIG. 1. In the drawing, the partial volume to be conveyed of the working chamber 10 is indicated by dash lines and according to FIG. 4 is considerably less than according to FIG. 1. As total result there is obtained the fact that the flow velocities in this narrow passage portion are with the arrangement according to the present invention considerably lower and the supply of energy for the exhaust operation is correspondingly lower. During the discharge of the working medium, a further advantageous effect is obtained by the opening edge 5b which is further advanced in the direction of rotation with regard to the opening edge 4b.

According to FIGS. 2 and 5, the rotary pistons occupy their dead center positions. Chamber 10 occupies a minimum of space, the so-called harmful space. When the opening 4 is in the center of the said harmful space as illustrated in FIG. 4, communication is established between the two halves of the chamber. Both halves are thus filled with a compressed working medium. The entire quantity which is entrapped in the harmful chamber 10 reexpands after the dead center point has been passed and reduces the intake quantity of the compressor.

According to FIG. 5, the opening edge 5b is in the center. The enveloping curve 6 will in its dead center position with the inner wall of the outer rotary piston 1 form a sealing gap 17 which subdivides chamber 10 into two parts and to a more or less extent prevents the compressed working medium from passing into the left chamber portion which increases prior to reaching the dead center point (see FIGS. 3 to 5). Therefore only or approximately only the right-hand chamber portion plus the opening space 5 forms the harmful space. As a result thereof, the re-expanding quantity is reduced while at the same time the intake quantity of the compressor increases.

It is, of course, to be understood that the present invention is, by no means, limited to the particular embodiment shown in the drawing but also comprises any modifications within the scope of the appended claims.

What I claim is:

1. A rotary piston compressor, which includes: an outer rotary piston having its inner wall surface shaped in conformity with a trochoid, an inner rotary piston rotatably arranged in and eccentrically located relative to said outer rotary piston and having its outer peripheral surface shaped in conformity with the contour of enveloping curves so as to form a plurality of surface sections

5 with each two adjacent surface sections intersecting each other along a line so as to form a ridge, the said surface sections together with the respective adjacent inner wall surface portions of said outer rotary piston defining portions of working chambers, the peripheral wall of said inner rotary piston being provided with a plurality of passage means respectively located between said ridges and when looking in the direction of rotation of said inner rotary piston being located closer to that ridge which is in front of the respective passage means than that ridge which is behind the respective passage means, and stationary insert means provided with fluid inlet and outlet means and operable successively to communicate with said passage means.

2. A compressor according to claim 1, in which that edge portion of said outlet means which defines the outlet end when looking in the direction of rotation of said inner rotary piston is displaced in the direction of rotation of the rotary compressor.

3. A compressor according to claim 1, in which each of said passage means of the inner rotary piston, when looking in the direction of rotation of the latter, starts approximately in the center of the respective enveloping curve defining the contour of the outer peripheral surface of the inner rotary piston and extends approximately over a quarter of said enveloping curve in the direction of rotation of said inner rotary piston.

4. A compressor according to claim 1, in which that edge portion of said passage means which in the direction of rotation of said inner rotary piston runs ahead of the opposite edge portion of the same passage means is greatly rounded toward the respective adjacent outer peripheral surface of said inner rotary piston.

5. A compressor according to claim 1, in which that edge portion of each of said passage means which runs behind the opposite edge portion of the same passage means when looking in the direction of rotation of the inner rotary piston is sharp-edged and sharp-angled with regard to the respective outer peripheral surface of said inner rotary piston.
